METHOD OF MANUFACTURING PULL MATCH
PACKAGES AND APPARATUS THEREFORWilly Lück, Stuttgart, Germany, assignor to Pull-
match Incorporated, New York, N. Y., a corpo-
ration of DelawareApplication June 29, 1936, Serial No. 87,819
In Germany March 14, 1934

13 Claims.

(Cl. 93—2)

The invention relates to the manufacture of pull match packages in which the match strips lie between cover strips corrugated to form pockets for the matches.

5 In manufacturing such packages a match strip is fed between two cover strips, which are joined together and cut into the proper lengths.

According to my invention the member feeding the match strip makes a pause after each insertion of a length of match strip for one pack-
10 age.

The invention includes apparatus embodying this feature, and other features which will be pointed out hereinafter.

15 An example of such apparatus is shown in the accompanying drawing, in which

Fig. 1 is an elevation of a portion thereof,

Fig. 2 a plan view, and

20 Fig. 3 a view from the left of Fig. 1, with parts removed.

In the machine shown there are three rolls 1, 2, 3 mounted in a frame 4. A toothed wheel 5 fixed to the roll 2 meshes with a toothed wheel 6 fixed to the shaft 20 of the roll 3. The rolls 1 and 2 have rings of teeth 8 and 7 respectively, for imparting a corrugated shape to a strip of cardboard or the like fed between them as indicated at a. The cardboard strip after leaving the bight of rollers 1 and 2 is entrained about the left-hand side of roller 2 and threaded between rollers 2 and 3. As shown in Fig. 3 the teeth are divided into groups of five, separated by much wider teeth, marked 7¹ in the case of the roll 2. A cam ring 10 with noses 9 is fixed 25 to the roll 2, which is driven.

The roll 3 serves as a feed roller for the match strip b and is mounted on a lever 11 pivoted at 12 to the frame 4. The roll 3 has two rings of teeth 3¹ engaging the matches, and the lever 11 carries a pawl 13 engaging the noses 9. On the lever 11 there is a bed 14 for a slide 15, on which a cutter wheel 16 is mounted, the slide being adjustable in relation to the roll 3 by means of a screw 17. Flanges 18 on the lever prevent the matches from dropping away from the teeth 3¹. The cutter wheel 16 is driven by a pinion 19 meshing with the wheel 6.

40 The cutter wheel cuts the web of the match strip at regular intervals, so as to divide it into sections, each with five matches, and the sections are carried by the roll 3 to position c, where the matches are laid in the corrugations of the cover strip. Each time a section has been so placed a nose 9 of the cam 10 strikes the pawl 13 so 45 that the lever 11 is lifted and the wheels 5 and 6

are disengaged from each other. Rotation of the roll 3 then stops, due to friction or to a brake 29 applied as to the shaft 20, and then the pawl becomes disengaged from the cam nose and the wheels 5 and 6 are brought into engagement again. In the example shown the noses 9 are of such width that the re-engagement of the wheels 5 and 6 takes place when the wheel 5 has rotated through an arc equal to the circumferential width of one tooth. 5

The pauses which occur in the feed of the matches to the cover strips have the effect of placing the sections of match strip between the covers with intervals between them. 10

The downward movement of the lever 11 may 15 be assisted by a spring, and is limited by a stop not shown, so that the wheels 5 and 6 enter into mesh smoothly.

The pitch of the teeth of the wheels 5, 6 corresponds with that of the wheels 7, 3¹, and also 20 with the spacing of the matches.

The noses 9 are preferably made of harder metal than the pawl 13, so that when wear occurs it can easily be corrected by renewing the pawl. The cam ring 10 is adjustable, as shown at 30, 25 and pawl 13 is adjustable, as indicated at 31, to enable the requisite precision to be obtained.

The second cover strip 32, which may be smooth, passes round the roll 3 and is laid against the match strip b. It travels between the rings 30 of teeth 3¹ and is stuck to the crest of the corrugations of the other cover strip. It may, alternatively, be fed from the right by the roll 3, as viewed in Fig. 1, an additional roll serving to press it against the cover strip with the matches 35 already laid thereon.

What I claim as my invention and desire to secure by Letters Patent of the United States is:—

1. Apparatus for the purpose set forth, comprising in combination a roll for continuously feeding a corrugated cover strip, a roll for feeding a series of matches to said cover strip, a lever carrying said second mentioned roll, a pinion fixed to said second mentioned roll, a toothed driving wheel fixed to said first mentioned roll and normally engaged by said pinion to drive said rolls and feed said corrugated cover strip and said series of matches together at the same rates of speed, and a cam whereby said lever is rocked at intervals for disengaging said pinion from said toothed wheel to interrupt the feed of said series of matches while continuing the feed of said corrugated cover strip. 40

2. Apparatus as claimed in claim 1, including 45

55

a brake for stopping at intervals the feed of the matches.

3. Apparatus as claimed in claim 1, including a cutter for cutting into sections a match strip fed towards the cover strip.

4. Apparatus for the purpose set forth, comprising in combination a roll for continuously feeding a corrugated cover strip, a roll for feeding a series of matches to said cover strip, a lever carrying said second mentioned roll, a pinion fixed to said second mentioned roll and a toothed driving wheel engaged therewith, and a cam whereby said lever is rocked at intervals for disengaging said pinion from said toothed wheel, the pitch of the teeth of the pinion and toothed wheel being equal to the pitch of the corrugations of the cover strip.

5. Apparatus for the purpose set forth, comprising in combination a roll for continuously feeding a corrugated cover strip, a roll for feeding a series of matches to said cover strip, a lever carrying said second mentioned roll, a pinion fixed to said second mentioned roll and a toothed driving wheel engaged therewith, and a cam whereby said lever is rocked at intervals for disengaging said pinion from said toothed wheel, the spacing of the groups of matches being regulated by means of the cam.

6. Apparatus for the purpose set forth, comprising in combination a roll for continuously feeding a corrugated cover strip, a roll for feeding a series of matches to said cover strip, a lever carrying said second mentioned roll, a pinion fixed to said second mentioned roll and a toothed driving wheel engaged therewith, a cam whereby said lever is rocked at intervals for disengaging said pinion from said toothed wheel, and a cutter mounted on the lever, for cutting into sections a match strip fed towards the cover strip.

7. Apparatus for the purpose set forth, comprising in combination a roll for continuously feeding a corrugated cover strip, a roll for feeding a series of matches to said cover strip, a lever carrying said second mentioned roll, a pinion fixed to said second mentioned roll and a toothed driving wheel engaged therewith, a cam whereby said lever is rocked at intervals for disengaging said pinion from said toothed wheel, a cutter mounted on the lever, for cutting into sections a match strip fed towards the cover strip, and means for adjusting the cutter on the lever.

8. The method of manufacturing match packages of the character described which comprises continuously feeding a first cover strip into match receiving position, feeding matches in groups to a position on the first cover strip in which the groups of matches are separated from each other by spaces, and thereafter attaching a second continuous cover strip in overlying relation to the

first cover strip to maintain the positioning of the matches.

9. The method of manufacturing match packages of the character described which comprises continuously feeding a cover strip into match receiving position, intermittently feeding a match strip into position on said cover strip to form a combined strip in which groups of matches are spaced apart on said cover strip, and placing a second cover strip over said matches to form a match package in which the matches are enclosed in spaced groups between the two cover strips.

10. The method of manufacturing match packages of the character described which comprises corrugating a first cover strip to provide a series of corrugations therein, feeding a match strip comprising a group of match stalks spaced from each other a distance equal to the spacing of the corrugations, bodily and laterally moving said match stalks into the corrugations of said cover strip, and similarly supplying to said corrugated strip a subsequent group of match stalks spaced from said first mentioned group by a distance greater than that of a corrugation.

11. The method of manufacturing match packages of the character described which comprises corrugating a first cover strip to provide a series of corrugations therein, supplying match stalks in a continuous strip with the stalks spaced apart a distance equal to the spacing of the corrugations, cutting the match stalk strip into lengths each comprising a group of match stalks, supplying a length so cut to one side of said corrugated cover strip in a position which places each match stalk in a separate corrugation, and similarly supplying to said corrugated strip a subsequent length of said match stalks spaced from said first mentioned length by a distance greater than that of a corrugation.

12. Apparatus for the purpose set forth comprising means for continuously feeding a first cover strip into match receiving position, means for feeding matches onto said first cover strip in groups and with the groups separated from each other by spaces, and means for feeding a second cover strip into attached relationship with said first cover strip to form a match package in which the matches are enclosed in spaced groups between the two cover strips.

13. Apparatus for the purpose set forth comprising means for continuously feeding a cover strip into match receiving position, means for intermittently feeding a match strip into position on said cover strip to form a combined strip in which groups of matches are spaced apart on said cover strip, and means for placing a second cover strip over said matches to form a match package in which the matches are enclosed in spaced groups between the two cover strips.
